CLAIM

The ornamental design for a container and lid of a blender, as shown and described.

DESCRIPTION

FIG. 1 is a bottom, front and right-side perspective view of the container and lid of a blender of our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In the drawings, the broken lines depict portions of the article and form no part of the claimed design.
